UNITED STATES PATENT OFFICE.

GASTON STROBINO, OF PATERSON, NEW JERSEY.

PHONOGRAPH MACHINE.

Application filed October 22, 1921. Serial No. 509,656.

To all whom it may concern:

Be it known that I, GASTON STROBINO, a citizen of the United States, residing at Paterson, in the county of Passaic and State 5 of New Jersey, have invented certain new and useful Improvements in Phonograph Machines, of which the following is a specification.

This invention relates to phonograph and 10 the like machines and particularly to the transmitters thereof. The principal objects of the invention are to construct a transmitter that will more faithfully reproduce sounds than those now commonly 15 used and at the same time reproduce them in ample volume; to provide a transmitter that may be used with equally good results on either lateral—or vertical—cut records; to provide a transmitter which will be 20 adapted to coact to good advantage with the hollow cover of an ordinary phonograph machine cabinet in amplifying the sounds and which, where said cover is hinged and so is movable from the upright or open 25 position to the horizontal or closed position, may be articulated into and held in housed relation to the cover preliminarily to moving the cover to closed position; and to provide an improved point-device or 30 needle for phonograph transmitters.

In the drawings,

Figures 1 and 2 are a front and a side elevation of a phonograph machine embodying my invention, the transmitter appearing 35 in folded or inoperative position;

Figures 3 and 4 are side and front elevations of the transmitter in position to co-operate with a lateral-cut record, parts of the transmitter supporting means appearing 40 in section in Fig. 3;

Figure 5 is a view in side elevation of the transmitter in one of the positions in which it will cooperate with a vertical-cut record, parts of the supporting means appearing 45 in section;

Figure 6 is a top plan view of the member *f* shown in Figs. 1 to 5;

Figures 7 and 8 are respectively a longitudinal section and a transverse section on 50 line 8—8, Fig. 7, and Figures 9 and 10 are respectively a longitudinal section and a transverse section on line 10—10, Fig. 9, of a certain joint, the parts of a joint in Figs. 7 and 8 on the one hand and Figs.

9 and 10 on the other, being in different 55 relative positions;

Figures 11 and 12 show in section and side elevation my improved point-device or needle in two different forms;

Figure 13 is a side elevation of a modified form of transmitter in position to co-operate with a vertical-cut record, the supporting means appearing partly in side elevation and partly in section; and

Figure 14 is an underneath plan view of 65 the transmitter shown in Fig. 13.

a is the record-platen compartment of a phonograph machine, *b* the hollow cover therefor hinged to *a* on a horizontal axis, *c* 70 is the record-supporting platen rotating on a vertical axis and *d* is a record on the platen.

My improved transmitter is characterized by a hollow resonating member *e* of thick 75 material and formed open to the atmosphere, thus simulating a bell in respect to its form, and function as a resonator; in the present adaptation it has the form of a concavo-convex shell. Surmounting and secured to this member *e* may be a smaller 80 and similar resonating member *e'*, *e''* being a stud rigidly upstanding centrally from member *e* and having member *e'*, at a central point thereof, rigidly secured thereto. 85 Member *e'* is not indispensable.

Resonator *e* has attached thereto, to its under side and at its rim, an elongated resonating member or arm *f*, the same having a preferably substantially half-bulbular inner end *f'* presented with its open side 90 toward the open side of the resonator *e* and having its outer end *f''* projecting beyond the perimeter of said resonator, the general relation of the member *f* to the resonator being that of a chord to a circle. The end *f''* is split and a bifurcated metal holder *g* for a needle or point-device *h* straddles its split portion and is held thereon by aligned studs *i* having clamping nuts *j* 95 which may be screwed up tight enough to put said split portion under sufficient tension to prevent any looseness of the holder and consequent production of induced sound and yet leave the holder free to move somewhat on the studs as a pivot; the point-device *h* is a plain or ordinary needle for lateral-cut records. The means 100 for attaching member *f* to member *e* may

be a simple plug or stud *k*; it fits each tightly, but the connection it affords is such (in the present case by the torsion of *k*) as to allow some yield of *f* relatively to *e* substantially on the axis of *k* as a pivot.

Somewhat less than forty five degrees from arm *f* anti-clockwise, viewing member *e* from above, are rigidly mounted on said member two other point-devices *l m*. They are preferably set in a block or clip *n* rigidly attached to the rim of resonator *e* and project in more or less spaced radii at a downward incline with respect to the rim. The former is a point-device for V-shaped and the latter a point-device for U-shaped vertical-cut record grooves.

The transmitter is movable to four positions, to wit: the position where it is folded or held up in the cover *b* out of operative relation to the record, and each of the positions where its point-devices *h l* and *m* respectively rest on the record. When in any of the positions in which it cooperates with the record it should be capable of movement horizontally or parallel with the face of the record and also up and down, and it should also be held at that time against shifting, by its own weight, out of the particular inclination to which it is set and which is appropriate to the particular point-device then in use. The transmitter is supported, so as to fulfill these requirements, as follows: *o* is a bracket attached to a wall of the cover *b* so that when the cover is in the open position an adjustable pin-bearing *p* in the upper arm *o'* of the bracket will be vertically above an adjustable pin-bearing *q* in its lower arm *o''*. A block *r* has an underneath socket-bearing *r'* for the bearing *q* and at the top a transverse slot *r''* in the bottom of which is a socket-bearing *r'''* for the lower end of a bearing pin *s* which can tilt on its lower end to a limited extent longitudinally of, but is held against sideways movement by, the slot, and which at the top has a socket-bearing *s'* for the bearing *p*. Block *r* has at its lower end and in planes parallel with slot *r''* a pair of ears *r''''* (the nearer one appearing in Fig. 3 and the other in Fig. 5) and in these on a clamping screw *t* is fulcrumed the free end of a stub *u* which is fitted substantially radially in the rim portion of member *e* and has an enlarged portion *u'* embraced by the split-collar *v* suitably secured to the member *e* (Fig. 3) and provided with a bolt *w* for clamping it to said stub. The portion *u'* of the stub has two arcuate grooves *u'' u'''* and connecting them a cut-away portion, or flat, *u''''* (Figs. 7 and 9) arranged about midway the length of each of them. Bolt *w* lies in the recess formed by the grooves and flat, and when the flat registers with the bolt the transmitter may be shifted one way or the other longitudinally of the stub and

thereupon rotatively a limited distance, to wit, until one or the other end of the groove then registering with the bolt impinges against the latter. The fit of the stud with respect to member *e* may be made sufficiently tight so that it may be turned thereon (but only by overcoming a certain amount of friction) by tightening bolt *w*. When the bolt coincides with the longer groove *u''* (Figs. 7 and 8) the transmitter may be turned anti-clockwise to the limit of the groove, which will bring member *e* to that inclination (Figs. 3 and 4—particularly Fig. 4) which is appropriate for the proper cooperation of point-device *h* with the record—which of course is assumed in this case to be a record with a lateral-cut groove; or the transmitter may be turned clockwise to the limit of the groove, which will bring it to such an inclination that upon then elevating it on pivot *t* and swinging it and block *r* on the vertical axis afforded the latter in bracket *o* it will be housed in the cover *b* with the its open side toward the observer (Figs. 1 and 2), in which position it may be held by the clip *x*. When the bolt coincides with the shorter groove *u'''* (Figs. 9 and 10) turning of the transmitter clockwise or anti-clockwise to the limit of the groove will bring it to either of two (relatively reverse) inclinations, one of which is appropriate for the point-device *l* and the other for the point-device *m* to properly cooperate with the record—which in such case would be a vertical-cut record with either a V-groove or a U-groove. In any case, when the transmitter is in operative relation to the record it may move freely horizontally around the vertical axis of block *r*, and it may move slightly and with perfect freedom up and down on pivot *q* under the influence of the rotating record, pin *s* rocking lengthwise of and in the slot *r''*, the joint between *r* and *u* being normally of such tightness (by turning screw *t* to cause *u* to be clamped between ears *r''''*) that *r* and *u* are immovable with reference to each other except when, in moving the transmitter to the folded position, the clamping resistance set up by the screw is overcome. That part of the mechanism which includes the pin *s* in a slot *r''*, having for its object to permit movement of the transmitter up and down under the influence of the rotating record and at the same time maintain pressure upwardly against the arm *o'* as well as downwardly against the arm *o''* of the bracket *o*, is substantially the same as in my Patent No. 1,430,700.

My principal object in the improving of phonograph transmitters has been to avoid the metallic effects and creation of secondary or induced sounds that attend the use of ordinary diaphragm transmitters and at the

same time provide a transmitter that could be used with either vertical- or lateral-cut records interchangeably. In my Patent No. 1,374,479 I aimed to accomplish this result by using a hollow membrane member having the arms of a fork-shaped free stylus device (terminating in a point-device) rigidly secured as to the arms thereof and only at the extremities of the arms to said member in the line of substantially its greater diameter. But in further experimenting I found that if the transmitter contained as to the part carrying the point-device a relatively thick vibratory portion, as a thick vibratory head on the free end of a vibratory arm of thin material suitably supported at a point remote from the head (see my Patent No. 1,430,700 already mentioned), the sound would be a better reproduction of the original. In still further experimenting I have now found that I can eliminate the thin arm and thereby produce an even better reproduction of the original sound as well as a complete elimination of metallic or other interfering or induced sound, and also considerably increased volume, if, instead of thin material being included as an active part of the transmitter, its thick part be formed with a concavo-convex portion, with the interior or cavity open to the atmosphere, as herein set forth. Just as the device of my Patent No. 1,430,700 will reproduce sound in appreciable volume without any amplifying auxiliary, so will the present transmitter do so; I therefore claim the present transmitter broadly, i. e., as consisting of a body of vibratory, that is, resonant, material formed thick throughout and including a concavo-convex portion with its interior or cavity open to the atmosphere, regardless of whether the point-device actually in use is attached specifically to said hollow portion or to some other part of said body. Thus said body in the present example includes arm *f*, although said arm is not integral with part *e* and in fact is capable of slight torsional yield relatively to member *e* around the axis of stud *k*, the purpose of the yield being to allow the point-device *h* to move up and down—as it endeavors to and does more or less “short-cut” the deflections of the (lateral-cut) groove for which this point-device is specifically intended—independently of the member *e*, whose weight would otherwise cause injury to the record, just as the purpose of the yield around axis *z* is to allow the point-device to adapt itself, independently of member *e*, to the lateral deflections of the groove. (The up-and-down yielding of a part of a thick vibratory transmitter body has already been set forth in my Patent No. 1,430,700 hereinbefore mentioned). I have shown member *f* extended inwardly, as at *f'* for the same reason that I have provided the member *e'*, which may

also be regarded as a part of the mentioned body, to wit, to increase the resonance of said body; neither of these expedients is, however, by any means indispensable.

Since the material for the forming of the transmitter body that has the proper resonance lacks sufficient weight to maintain it in good contact with the record—i. e., against a tendency to over-vibration or dancing—I find it usually expedient to provide a weight, as *y*, attaching it to the block *r*.

In Figs. 13 and 14 the parts *a* to *d* and *o* to *t* are the same as described above. Here the body of resonating material formed thick throughout includes the hollow gong-shaped member *z*, a shank *2* to which member *z* is secured (with its open side facing away from the same), and an arm *3* which is secured to the shank. The point-devices *4*, *5* for V-shaped and U-shaped vertical-cut records are set in the rim of member *z*, which may be turned on the axis of stud *2'* (by which it has a friction-fit connection with the shank) to bring one or the other of said devices against the record, its open side being then down. When the transmitter is inverted the point-device *6* for lateral-cut records, which is carried by the holder *7* rigidly secured to the end of arm *3*, comes into position to cooperate with a record, arm *3* affording the aforementioned movability of the point-device *6* relatively to the structure including the shank and member *z* by being then bodily yieldable laterally or parallel with the record and also up and down because of a certain amount of flexion and torsion possible in the screw or stud *3'* by which it is secured with a rocking contact against the side of shank *2*. The shank has a split-collar *8* receiving the end of a stub *9* and having a screw *10* to clamp it thereto, said stub being clamped between the ears *z'* of the block *r* by the screw *t*.

In experimenting with needles or point-devices of the class in which the record contact part is some hard substance, as a jewel, arranged in a setting I have found that the sound given off when such a device is in action is made of greater depth of tone and richness if, first, the setting presents a broad shoulder more or less in a plane at right angles to the axis of the device and, second, the setting is without the usual long tang or shank and is adapted to be itself sunk more or less deeply in the structure which carries it. Figs. 11 and 12 show point-devices embodying these features, Fig. 11 showing one for a V-shaped and Fig. 12 one for a U-shaped vertical groove. The actual, though not indispensable, construction shown is a shell *11* of the form of a truncated cone containing a filling of lead *12* in which the contact part *13* is set and having a rearward eye or hook *14*. This device is set bodily in a conforming socket or

hole in the resonating body and may be held therein by a pin 15 (Fig. 13) which is passed into said body and through the eye 14.

Such a resonating body as constitutes the principal feature of my invention is peculiarly fitted to develop to full effect the sound-amplifying quality of a hollow contiguous element of the form and nature of the usual hollow cover *b* of a phonograph machine cabinet because the tones or sounds set up by such a transmitter are full and well-rounded replicas of the originals. To bring out fully the amplifying quality of the element *b* it is of course best if the transmitter be attached thereto, and this I do in such manner as to preserve the fullness and roundness of the original sound, and so as to eliminate induced or interfering sounds, by forming the parts *u* *r* and *o* of the intermediary structure thick and of course of resonant material and with tight joints, it being remarked that in the operative or playing position of the transmitter even the joint between *o* and *r* is a tight one because at that time parts *s* and *r* are exerting spreading tension on the arms of bracket *o*.

An important feature of my invention is that the resonating body is formed in sections in vibration-transmitting contact with each other and that these sections have different pitch, the point-device being secured in vibration-transmitting relation to the section having the higher pitch. Thus the pitch of the part *n* (which is of resonant material) or part *f* in Figs. 1 to 6, or that of the part *z* or part 3 in Figs. 13 and 14, is higher than that to which such part in any of these cases is secured, the difference in pitch being in the present example due mainly to the difference in size or bulk. Where the entire body has the same pitch there is too great disparity between the frequency of the vibrations of the point-device and that of the vibrations of said body, so that not only is the full resonance of said body not developed but its vibrations re-act too violently on the point-device, so that it tends to dance or jump more or less over the record; where the body is made in sections of different pitch, with

the point-device attached to the section having the higher pitch, there occurs a stepping-up of the vibrations in said body, i. e., from higher to lower frequency, so that the full resonance of the body is not only brought out but the section having the higher pitch becomes in effect a damper between the section having the lower pitch and the point-device, thus reducing the tendency to interfere with the proper travel of the point-device over the record. 55

Having thus fully described my invention, what I claim as new and desire to secure by Letters Patent is:— 65

1. A phonograph transmitter consisting of a resonant body including two thick portions having a torsion-connection with each other, in combination with a record-contacting point-device secured to one of said portions, the other of said portions being adapted to be held out of contact with the record with the axis of said torsion-connection out of perpendicular relation to the record. 70

2. A phonograph transmitter including a point-device to rest on a record, and a resonant structure having means to attach it to a suitable support and also having said point-device attached thereto, the portion of said structure to which the point-device is attached being yieldable toward and from and also laterally of the record relatively to the portion of said structure having said means. 75

3. In a mounting for the horizontally swinging transmitter of a phonograph machine, the combination of opposite upper and lower spaced supporting members and, between them, a horizontally swinging member, the swinging member having a pivoting engagement with one of the supporting members, and a pivot device arranged between the other supporting member and swinging member, one of the latter two members having a pivot-bearing for said device and the other a slot affording a pivot bearing for said device and confining said device against movement transversely thereof while allowing tilting of said device therein lengthwise of the slot. 80 90 95 100

In testimony whereof I affix my signature.
GASTON STROBINO.
